SHIRT ENVELOPE

of New York

Application June 5, 1931, Serial No. 542,343

2 Claims. (Cl. 223—18.6)

My invention relates to improvements in shirt envelopes, and more particularly, has reference to and is illustrated in the accompanying drawing in its application to an article of the class described adapted to support or suspend the shirt 5 within the envelope, while at the same time, providing means for hanging the envelope independently of such supports.

Referring to said drawing, Fig. 1 illustrates in perspective, the lower part being broken away, a 10 suitable form of shirt envelope with a shirt therein, the same embodying an application of my invention. Fig. 2 is a similar view with the shirt removed.

Referring to Figs. 1 and 2, it will be observed 15 that the shirt support or envelope comprises a back portion 5, having a forwardly and downwardly turned portion 6, cut out at the center, as indicated at 7, to allow for clearance of the shirt neck-band or collar. When a shirt, such as 8, 20 is used, the inturned free ends 9, 9', of the cut out portion serve to engage beneath the collar to retain the shirt within the envelope and to give stiffening and support to the collar, while at the same time, the flap 10 engages beneath the collar for giving additional support to the shirt, and the envelope may be provided with hanger holes 11 for hanging the same. 60

I claim:

1. A shirt support of the character described having a board-like portion adapted to be parallel with the body of the folded shirt, and an upper turned down portion cutaway at the center and extending inwardly at the ends to embrace the neck of the shirt. 65
2. A shirt support of the character described having a board-like portion adapted to be parallel with the body of the folded shirt, and an upper turned down portion cutaway at the center and extending inwardly at the ends to embrace the neck of the shirt, said cutaway portion separated at the bottom to expose part of the shirt. 70
